James O'Kelly, INVENTOR.

BY
Geo. F. Bimmel. ATTORNEY.

UNITED STATES PATENT OFFICE.

JAMES O'KELLY, OF ONEONTA, NEW YORK.

COMBINATION LOCK.

Application filed October 28, 1922. Serial No. 597,546.

To all whom it may concern:

Be it known that I, JAMES O'KELLY, a citizen of the United States, residing at Oneonta, in the county of Otsego and State 5 of New York, have invented certain new and useful Improvements in Combination Locks, of which the following is a specification:

This invention relates to a combination 10 lock designed primarily for use for locking slide or swinging doors, but it is to be understood that a lock, in accordance with this invention can be employed for any purpose wherein it is found applicable, and the invention has for its object to provide a lock 15 of such class, in a manner as hereinafter set forth, with means to prevent the opening thereof surreptitiously or by any one not familiar with the necessary adjustment 20 thereof to move the lock elements to a position to permit of the actuation of the lock to release the element held thereby in locked engagement.

Further objects of the invention are to 25 provide a combination lock which is simple in its construction and arrangement, strong, durable, compact, thoroughly efficient in its use, readily assembled, and comparatively inexpensive to manufacture.

With the foregoing and other objects in view, the invention consists of the novel construction, combination and arrangement 35 of parts, as hereinafter more specifically described and illustrated in the accompanying drawings, wherein is shown an embodiment of the invention, but it is to be understood that changes, variations and modifications can be resorted to which come within the scope of the claims hereunto appended.

In the drawings wherein like reference characters denote corresponding parts throughout the several views:—

Figure 1 is a front elevation of a combination lock, in accordance with this invention, showing the adaptation thereof in connection with the sliding door of a freight car, the lock bolt and latching element being illustrated in dotted lines,

Figure 2 is a longitudinal sectional view 50 of the lock and further showing the adaptation of the lock in connection with a latching element carried by a door,

Figure 3 is a sectional plan of the lock,

Figure 4 is a section on line 4—4, Fig- 55 ure 3,

Figure 5 is a section on line 5—5, Figure 3,

Figure 6 is a perspective view of one of the toothed locking disks,

Figure 7 is a face view of the dial plate, 60

Figure 8 is a rear elevation of a spring controlled locking bolt.

A combination lock in accordance with this invention, is illustrated, by way of example, for securing the sliding door of a 65 freight car, but it is to be understood that the lock can be employed with respect to the securing of any element to which the lock can be attached, and referring to the drawings in detail 1 denotes the body portion of 70 a freight car, 2 a door opening, and 3 a slidable door for closing the opening 2. The sill of the opening 2, is indicated at 4, and one side of the door frame is indicated at 5. The body portion 1, at its side, is cut away 75 for the purpose of mounting in the side of the body 1, of the car, in proximity to the opening 2, that is at one side of the latter a casing 6, secured in position by hold-fast devices 7, and having its front formed with 80 an opening 8, so that access can be had to actuate the locking mechanism which is enclosed by the casing 6. The front of the casing 6, has secured thereto, a pair of parallel and spaced guide bars 9, between which 85 is slidably mounted a closure plate 10, for concealing the dial disks, as well as the actuating or operating means for shifting the elements of the lock to released position. The closure plate 10, has a knob 11, to provide for the convenient shifting of the latter when the plate 10, is positioned to conceal 90 the dial disks and operating means of the lock. The plate 10, is secured in such position by a seal, as indicated at 12. The front 95 of the casing 6, has an apertured bracket 13, against which is positioned an apertured lug 14, on the plate 10, and through the lug 14, and bracket 13, extends the seal 12.

The door 3, on its inner face, has secured thereto, by the hold-fast devices 15, a latching element 16, which when the door 3, is closed, extends through an opening 17, formed in the side 5, of the door frame. The latching element 16, is notched as at 100 18, and when the door 3, is closed, the latch element extends within the body of the car, and inwardly with respect to that side of the body of the car to which is secured the casing 6. The latch element 16, when the 105

door 3, is closed, is adapted to be engaged by the locking bolt of lock, as clearly shown in Figures 1 and 2, whereby the door is securely fastened, and will be retained in such position until the locking bolt is shifted clear of the latching element.

Fixedly secured within the casing 6, is the lock casing 19, which is positioned against the inner face of the rear wall of the casing 6, and also against the inner face of the rear end wall of the casing 6. The lock casing 19, is spaced from the front end of the casing 6, by a block 20, and said lock casing 19, is of less width and of less length than the casing 6.

Arranged within the casing 19, on the inner faces of the front and back walls thereof, are longitudinally extending spaced guides 21, in which is slidably mounted, a releasing slide 22. Connected to the slide 22, by an eye 23, is a flexible member 24, which extends through an opening 25, formed in the forward end wall of the casing 19, and passes around a grooved pulley 26, which is carried by a bracket 27, secured to the side 5, of the door frame.

Arranged above the bracket 27, as well as being secured by the hold-fast devices 28, to the side 5, of the door frame are angle shaped brackets 29, through which extends a locking bolt 30, the latter having its lower end connected as at 31, to the flexible member 24. The locking bolt 30, has its upper end provided with a beveled head 31, and below the latter, the bolt 30, is formed with a lug 32, which bears against a plate 33, the latter is connected to the bracket 29, by a pair of expandable and contractile coiled springs 34, the function of which is to normally maintain the bolt 30, projected. The inner end of the latching element 16, is beveled as at 35, and when the door 3, is mounted to closed position, the beveled end 35, of the latching element riding against the head 31, of the bolt 30, will depress the bolt 30, until the opening 18, in the latching element 16, is shifted to a position over the head 31, of the bolt 30, and at this point the expanding of the springs 34, will force the head 31, into the opening 18, thereby locking the door 3.

The front and rear walls of the casing 19, each has its inner face provided with a vertical groove 36, for the purpose of mounting the polygonal shaped pintles 37, of the supporting shaft 38, within the casing 19. The shaft 38, is non-rotative and has mounted thereon, a plurality of locking disks, which are capable of being rotated on the shaft 38, and as shown, by way of example, four locking disks are employed and which are indicated at 39, 40, 41 and 42. Each of said locking disks is in the form of a gear and provided with peripheral teeth as indicated at 43, and each of said locking

disks is furthermore provided with a radially disposed slot 44, into which is adapted to extend the slide 22, when the locking mechanism is actuated to release the bolt from locking position with respect to the latching element 16. When the slide 22, is shifted for the purpose of releasing the locking bolt 30, the locking disks 39 to 42, are shown positioned so that the slots 44, will align so that the slide 22 can be shifted into all of the locking disks simultaneously. The slide 22, cannot be shifted to release the bolt 30, until all of the locking disks have been adjusted so that the slots of said disks will be arranged in parallelism. The locking disks are provided with lateral hubs 45, for maintaining them in spaced relation with respect to each other and further to prevent the shifting of the locking disks lengthwise of the shaft 38.

Associated with the locking disks 39 to 42, is a series of setting wheels which are employed for the purpose of shifting the locking disks to cause the arranging of the slots 44, in parallelism to permit of the slide 22, being shifted to release the locking bolt 30. Meshing with the locking disk 39, is a toothed setting wheel 46, meshing with the locking disk 42 is a toothed setting wheel 47, meshing with the locking disk 40, is a toothed setting wheel 48, and meshing with the locking disk 41, is a toothed setting wheel 49.

Journalized in the front and rear walls of the casing 19, is a series of shafts 50, 51, 52 and 53. The shaft 50, is arranged over the shaft 51, as well as being parallel thereto and is also arranged forwardly of the shaft 38. The shaft 52, is arranged over the shaft 53, as well as parallel thereto and further arranged rearwardly of the shaft 38. Carried by and rotated with the shaft 50, is a setting wheel 46, carried by and rotated with the shaft 51, is a setting wheel 47, carried by and rotated with the shaft 52, is a setting wheel 48, carried by and rotated with the shaft 53, is a setting wheel 49. The setting wheels 46 to 49, are always in mesh with the locking disks 39 to 42, respectively.

The front wall of the casing 19, is inset as at 54, 55, 56 and 57, forming recesses and in which are arranged the graduated dial disks 58, 59, 60 and 61, respectively. The disks 58, 59, 60 and 61, are integral with the outer ends of the shafts 50, 51, 52 and 53, respectively, and each of said shafts is furthermore provided with a knob 62, which projects from a dial disk and provides the means for the convenient actuation of the shaft.

Each of the shafts 50, 51, 52 and 53, is threaded, for a portion of its length, to receive a lock nut 63, which in connection with a collar 64, carrying a set screw 65, fixedly secures a setting wheel in position on its

respective shaft. Stop collars 50' are carried by the shafts 50 to 53.

Journalized in the casing 19, rearwardly with respect to the shafts 52, 53, and preferably in parallelism with respect to the shaft 38, is an operating shaft 66, which projects outwardly from the front wall of the casing 19, and is formed with a lever arm 67, to provide for the actuation of the shaft 66, for the purpose of releasing the bolt 30, from engagement with the locking element 16. The shaft 66, has secured thereon, intermediate its ends, a grooved mutilated pulley 68, to which is connected as at 15 69, a flexible pulling member 70, which is attached by the eye 71, to the slide 22. The pulling member 70, extends rearwardly from the slide 22, and over the shaft 38, and is adapted to shift the slide 22, into the 20 slots 44, against the action of the springs 34, when the locking disks 39 to 42, have been adjusted to a position whereby the slots 44, will be arranged in parallelism.

Connected to the slide 22, and projecting rearwardly therefrom, is a pair of throw-out arms 72, having a hooked rear end 73, which are permanently in engagement with the locking disks 40 and 41, and the function of the arms 72, is to shift the locking 25 disks 40 and 41, from set position after the bolt 30, has been shifted to release the locking element 16, and when pressure has been removed from the lever 67. When the lever 30, has been released by the operator, after the bolt 30, has been shifted from locking engagement with the locking element 16, the expansive action of the springs 34, will shift the bolt 30, upwardly, which carrying the flexible member 84, therewith, will move 35 the slide 22, out of the slots 44, and as the slide 22, moves forwardly, the throw-out arms 72, will be carried therewith, causing the shifting of the disks 40 and 41, and moving the slots 44, out of alignment with the other of the slots, and as the disks 40 and 41, are shifted, the setting wheel 46, will also be shifted and by this action the set combination will be destroyed so that it will 40 be impossible for any unauthorized person to ascertain the correct combination from the dials, due to the fact that after the locking disks have been shifted in the manner as stated, an incorrect combination will be shown by the dials.

By way of example, a combination is illustrated in Figure 1, of the drawings as 40, 10, 15, 20, carried by the dials 54, 55, 56 and 57, respectively and when the combination numbers have been arranged to align with the pointers 64, the locking disks will then be positioned whereby the slots 44, thereof will be in parallelism and when the shaft 66, is actuated through the medium of the lever arm 67, the slide 22, will be pulled rearwardly and enter the slots 44, which

provide for the moving of the bolt 30, from engagement with the locking element 16.

It is readily apparent that, unless all of the locking disks are shifted so that all of the slots 44, will be in parallelism, it will 70 be impossible to move the slide rearwardly a sufficient distance to shift the locking bolt 30 to released position, since but one disk unadjusted would be sufficient to arrest the rearward movement of the slide.

The top 75, of the casing 19, is removable, for the purpose of adjusting and changing the combination, or for other purposes. Whenever it is desired to adjust the position of any one of the setting wheels to 80 change the combination, the cover is removed, and the lock nuts holding the setting wheels in position are loosened, and the setting wheels are then set out of mesh with the locking disks, and these latter are 85 slightly turned. The setting wheels are then secured in position and the foregoing adjustment provides for a new combination. Whenever a new adjustment is had, it will 90 be necessary to note the numbers at which the dial disks are set in order to ascertain the new combination, after which the setting wheels should be given a few turns so that no unauthorized persons may ascertain the 95 new combination.

By slight changes in the position of the lock bolt and the location of the latching element secured to the door, and also increasing the length of the flexible member 25, the lock can be employed in connection 100 with swinging or other doors, and it is also obvious that the lock can be employed whether positioned with respect to the inside or outside of the door, although the example shown illustrates the lock as being 105 positioned with respect to the inside of the door.

Each of the locking disks although operating on the same shaft revolve and turn independently with respect to each other and each of the setting wheels meshes with and revolves a locking disk independently. By this arrangement, it requires a key figure or indicator for each of the dials, and this must be known to a person desiring to open the door or to actuate the lock to release the door.

The foregoing description taken in connection with the accompanying drawings, 120 describes and illustrates the preferred embodiment of the invention, but it is to be understood that changes in the detail of the construction can be had without departing from the spirit of the invention.

What I claim is:—

1. A combination lock comprising a plurality of toothed locking discs, each provided with a slot, means meshing with said disks for independently shifting them to cause the positioning of the slots in paral-

- allelism, a spring controlled locking bolt, a 45
slidable member connected with said bolt and adapted to be shifted in the slots when arranged in parallelism, thereby providing 50
5 for the moving of the bolt to released position, a flexible element connected to said slide-
able member, and means for winding said flexible element to shift the slideable member into the slots when positioned in parallelism thereby shifting the bolt to released position. 55
2. A combination lock comprising a plurality of toothed locking disks, each provided with a slot, means meshing with said disks for independently shifting them to cause the positioning of the slots in parallelism, a spring controlled locking bolt, a 60
slidable member connected with said bolt and adapted to be shifted in the slots when arranged in parallelism, thereby providing 65
10 for the moving of the bolt to released position, a flexible element connected to said slide-
able member, means for winding said flexible element to shift the slideable member into the slots when positioned in parallelism thereby shifting the bolt to released position. 70
15
- 20
- 25
- 30
- 35
- 40
3. A combination lock comprising a plurality of toothed locking disks, each provided with a slot, means meshing with said disks for independently shifting them to cause the positioning of the slots in parallelism, a spring controlled locking bolt, a 75
slidable member connected with said bolt and adapted to be shifted in the slots when arranged in parallelism, thereby providing 80
for the moving of the bolt to released position, a flexible element connected to said slide-
able member, means for winding said flexible element to shift the slideable member into the slots when positioned in parallelism thereby shifting the bolt to released position. 85
4. A combination lock comprising a pair of oppositely disposed flexible members, a spring controlled locking bolt connected to one of the said members, a slideable element attached to said flexible members and shifted in one direction by said spring controlled locking bolt, locking disks normally preventing the shifting of said slide in the opposite direction, means for adjusting said disks to provide for the shifting of said slide in the opposite direction, causing thereby the release of the locking bolt, and means connected to the other of said flexible members for shifting the slide in said opposite direction to release the locking bolt. 90
5. A combination lock comprising a pair of oppositely disposed flexible members, a spring controlled locking bolt connected to one of the said members, a slideable element attached to said flexible members and shifted in one direction by said spring controlled locking bolt, locking disks normally preventing the shifting of said slide in the opposite direction, means for adjusting said disks to provide for the shifting of said slide in the opposite direction, causing thereby the release of the locking bolt, means connected to the other of said flexible members for shifting the slide in said opposite direction to release the locking bolt, and means carried by the slide and engaging one of said disks for shifting it to locking position when the locking bolt moves to operative position. 95

In testimony whereof, I affix my signature.

JAMES O'KELLY.
